UNITED STATES PATENT OFFICE.

MICHAEL B. BOWEN, OF DECATUR, ILLINOIS, ASSIGNOR TO FARIES MANUFACTURING COMPANY, OF DECATUR, ILLINOIS.

DESIGN FOR A CEILING PLATE FOR ELECTRIC-LIGHT FIXTURES.

Application filed February 4, 1929. Serial No. 29,897. Term of patent 3½ years.

To all whom it may concern:

Be it known that I, MICHAEL B. BOWEN, a citizen of the United States, residing at Decatur, in the county of Macon and State of Illinois, have invented a new, original, and ornamental Design for a Ceiling Plate for Electric-Light Fixtures, of which the following is a specification, reference being had to the

accompanying drawing, forming a part thereof.

Figure 1 is an elevational view, and Figure 2 is a plan view showing my new design.

I claim:

The ornamental design for a ceiling plate for electric light fixtures as shown.

MICHAEL B. BOWEN.
